[57] CLAIM

The ornamental design for a combination key holder and miniature photo album, as shown and described.

DESCRIPTION

FIG. 1 is a perspective view of a combination key holder and miniature photo album showing my new design;

FIG. 2 is a right end view thereof;

FIG. 3 is a left end view thereof;

FIG. 4 is a top plan view thereof;

FIG. 5 is a bottom plan view thereof;

FIG. 6 is a left side view thereof;

FIG. 7 is a right side view thereof; and,

FIG. 8 is a perspective view showing the photo album in open position.
The broken lines in FIG. 8 are for information only, and form no part of the instant design.
